CUP OR SIMILAR ARTICLE

Philip Thomas Gallagher, East Goshen Township, Chester County, Pa., assignor to The Alan I W Frank Corporation, Pittsburgh, Pa., a corporation of Pennsylvania

Filed June 30, 1969, Ser. No. 17,944

Term of patent 14 years

Int. Cl. D7—01

U.S. Cl. D44—9

The figure is an isometric view of a cup or similar article embodying my new design, it being understood that the ornamental band is continuous about the periphery of the cup.

The characteristic feature of the design resides in the ornamental band.

I claim:

The ornamental design for a cup or similar article, as shown and described.
